CUTTING DIE

John M. Wall and Jacob W. Albrecht,
Syracuse, N. Y.

Application April 26, 1940, Serial No. 331,834

7 Claims. (CL 164—29)

This invention relates to cutting or blanking dies intended primarily for cutting blanks from fibrous material such as leather, cloth, paper, etc. As for example, blank parts for the manufacture of shoes, pocketbooks, boxes, and the like. It is customary to spread the material being cut upon the buck or platen of a press and the dies are placed by hand on the material. The dies are then pressed into engagement with the material by the head of the press. After the blanks have been severed from the material, the dies are removed from the press by hand. This method permits any die, or group of dies, to be used on the same press and permits the operator to select the desired portions of the material for the cutting of the respective blanks. Heretofore, dies of this type have been constructed in various manners as for example a cutting blade secured to the peripheral edge of a wood core as by screws, clamps, or other suitable means.

Another method of constructing these dies is to use a comparatively thick heavy cutting blade which is bent to the desired shape and the abutting ends of the blade welded together. Dies have also been constructed by first forming a metal core to the shape of the blank and subsequently welding a cutting blade to the periphery of the core. The wood core die is not satisfactory in that it is not durable and does not hold its shape. The heavy metal cutting blade construction materially increases the cost of the die and it is difficult, if not impossible, to use this construction in forming complicated die shapes having small or sharp projections. The metal core dies is not only expensive, but prevents the operator from inspecting the material while he is placing the die thereon.

This invention has as an object a die of the type referred to embodying a particularly novel construction employing a thin, flexible, cutting blade which may be conveniently bent or shaped to any complicated form. The construction further embodies reinforcement for the formed blade, the completed die being exceptionally rigid and durable with no core to obstruct the inspection of the material being cut, and the die being extremely light in weight.

An important feature of the invention resides in the reinforcement of the cutting blade which is accomplished by a truss formation which is light in weight but extremely rigid.

The invention consists in the novel features and in the combinations and constructions hereinafter set forth and claimed.

In describing this invention, reference is had to the accompanying drawing in which like characters designate corresponding parts in all the views.

Figure 1 is a top plan view of a die partly in section embodying our invention.

Figure 2 is a sectional view taken on line 2—2, Figure 1.

Figure 3 is a fragmentary elevational view illustrating the cutting blade and truss member 5 with the outer reinforcing member removed.

Figure 4 is a sectional view taken on line 4—4, Figure 3.

Figure 5 is a top plan view, similar to Figure 1, illustrating a plurality of dies arranged in a cluster.

Figure 6 is a view, similar to Figure 1, illustrating a modified form of our invention.

Figure 7 is a sectional view taken on line 7—7, Figure 6.

Figure 8 is a fragmentary side elevational view of the cutting blade employed in the construction shown in Figures 6 and 7.

The invention consists generally of a cutting blade member formed of thin, flexible material such as steel bent or shaped to the desired form and the abutting ends welded or otherwise integrally secured together, a reinforcing member bent to a shape substantially complementary to the shape of the cutting blade member and extending in parallel spaced relation thereto. One of said members is provided with a plurality of spaced projections or protuberances arranged in a truss formation and being fixedly secured to both of said members to form an integral die unit.

Referring to Figure 1, the cutting blade member is designated 10 and is formed of thin, flexible material, preferably steel, which has been previously heat treated to provide proper cutting edges 11. It is to be understood that the thickness of the blade 10 and of the other parts are exaggerated in the drawing for the purpose of clarity, the drawings indicating only the relative arrangement of the elements of the construction.

In the die illustrated in Figure 1, the blade 10 is provided with inwardly extending bights 12 and an outwardly extending bight 13. Because of the thinness and flexibility of the blade 10 the same may be conveniently bent at sharp angles to produce a die of irregular or complicated form.

The formed cutting blade employed is retained in shape by a truss formation. This truss formation is produced by providing the cutting blade member with a plurality of triangular shaped projections. In Figures 1 to 5, these projections or protuberances are formed by encircling the formed blade with a sinuous strip of flexible metal and attaching the same at the bases 14 of the projections to the blade 10. That is, the strip 55 is secured to the blade as by spot welding the strip thereof intermediate the uniformly spaced triangular projections 15. As illustrated in Figures 1 to 5, the sinuous strip is secured to the outer side of the blades 10. It will be apparent 40 as the description proceeds that this strip, to-

gether with the outer reinforcing member, may be arranged on the inner side of the blade if desired. However, I have found it more convenient and economical in the manufacture of these dies to arrange the reinforcing truss work on the outer side of the blade.

The outer apexes or peaks 16 of the triangular projections are encircled by a reinforcing member 17 preferably in the form of a flat metal strip, and are fixedly secured thereto as by spot welding. This construction produces a particularly rigid and durable die, it being impossible for any portion of the cutting blade member 10 to move out of shape because of the fact the converging sides of the projections form a truss resisting movement in both directions. This construction also permits the convenient formation of complicated die shapes. In Figure 1, the blade 10 is properly bent to provide irregular projections such as the bights 12, 13, and these bight portions are maintained in shape by securing a reinforcing strip across the opening of the bight. For example, the strip 18 is welded to the blade 10 and extends across the bights 12, and the strip 19 bridges the bight 13. The sinuous truss strip and the reinforcing strips 17, 18, 19 are arranged intermediate the side edges of the blade 10 and are of less width, whereby both of the cutting edges 11 may be employed.

In Figures 6 to 8, the triangular truss projections are formed integral in the blade 10 by forming the blade with conical portions 20, the apexes of which are welded to the reinforcing strip member 17. This construction is particularly economical in the manufacture of dies of more or less uniform shape, the curved portions of which are formed on comparatively large radii.

In both embodiments referred to, the blade 10 is provided with protuberances arranged to effect a truss formation. However, these protuberances or projections may be initially secured to or formed from the reinforcing strip 17. The projections have been referred to as of triangular formation. In both instances, the projections are not of true geometric triangular formation, but in the nature of truncated triangles in order to provide sufficient surface to effect a proper welding area on both the blade and the reinforcing strip 17. The important feature is that the sides of the projection converge to effect a truss formation whereby, when the projections are fixedly secured at their apexes to the blade and reinforcing member, the cutter blade is firmly secured in shape.

It will be obvious that dies embodying our invention are extremely light and the entire surface of the material being cut is open for clear inspection by the operator. By arranging the truss work to encircle the cutting blade, we find the reinforcement construction serves as a convenient means for the operator in handling the dies by hand.

Figure 5 illustrates how the construction readily permits the formation of a cluster of two or more dies to form multiple blanks. As shown in Figure 5, the two dies are of similar formation with the similarly curved portions 22 arranged in adjacent relationship. Both of the dies are encircled by the reinforcing strip 17 with the sinuous truss strip arranged intermediate the cutting blades and the strip 17. We have found that

the overlapping portions 22 of the dies do not need reinforcing if such portions are of comparatively short length, as shown in Figure 5.

What we claim is:

- 5 1. A cutting die comprising a cutter blade bent to the desired form, a reinforcing member comprising a thin, flexible, strip extending parallel with said blade and in spaced relation thereto, the spacing means being obtained by spaced conical protuberances formed in one of said members, and the peaks of said protuberances being fixedly secured to said other member, said blade being formed with a plurality of spaced triangular projections arranged in truss formation intermediate said blade and strip, and said projections being fixedly secured to said blade and strip.
- 10 2. A cutting die comprising a cutter blade member bent to the desired form, a reinforcing member comprising a thin, flexible, strip extending in parallel spaced relation to said cutter blade member, the spacing means being obtained by spaced conical protuberances formed in the body of the blade midway of its cutting edges, and the peaks of said protuberances being fixedly secured to said flexible strip, one of said members being formed with a plurality of spaced triangular projections arranged in truss formation and said projections being fixedly secured to said members to form a rigid integral unit.
- 15 3. A cutting die comprising a cutter blade member shaped to the desired form, a reinforcing member comprising a thin, flexible, strip extending in parallel spaced relation to said cutter blade member, one of said members being provided with spaced protuberances having inclined side walls converging to a peak, and the peaks of said protuberances being fixedly secured to said other member to form a rigid integral unit.
- 20 4. A cutting die comprising a cutter blade member and a reinforcing member, said members being bent to the desired form and extending in spaced relation, a sinusoidal truss member arranged intermediate said cutting blade member and said reinforcing member and being fixedly secured at the apexes thereof to said members respectively to form an integral unit.
- 25 5. A cutting die comprising a cutter blade member and a reinforcing member, said members being shaped to the desired form and extending in spaced relation, one of said members being formed with a plurality of spaced conical projections, and said other member being fixedly secured to the apexes of said projections to form an integral unit.
- 30 6. A cutting die comprising a cutter blade consisting of a thin, flexible metal strip shaped to the desired form, a strip of metal encircling the blade and being formed with spaced projections having converging sides and being welded to the blade intermediate said projections, a reinforcing strip encircling said projections and being welded to the apexes of said projections to form an integral unit.
- 35 7. A cutting die comprising a cutter blade consisting of a thin, flexible, metal strip shaped to the desired form, said blade being formed with integral spaced conical projections, a reinforcing strip encircling said projections and being welded to the apexes thereof to form an integral unit.
